United States Patent Office

Des. 208,308
Patented Aug. 15, 1967

208,308

DATA STORAGE UNIT

Donald H. Wood, Santa Clara, and David L. Brodsky,
Richard N. James, and Willard E. Roth, San Jose, Calif.,
assignors to International Business Machines Corpora-
tion, Armonk, N.Y., a corporation of New York

Filed Aug. 11, 1966, Ser. No. 3,421

Term of patent 14 years

(Cl. D26—5)

The figure is a perspective view taken from the front and one side of a data storage unit showing our new design, the rear and side not shown being substantially plain and unornamented.

We claim:

The ornamental design for a data storage unit, as shown and described.
